UNITED STATES PATENT OFFICE

143,527

DESIGN FOR AN EDUCATIONAL GAME BOARD

Julian J. Faberman, New York, N. Y.

Application August 25, 1945, Serial No. 121,633

Term of patent 14 years

(Cl. D34—5)

To all whom it may concern:

Be it known that I, Julian J. Faberman, a citizen of the United States and a resident of New York, in the county of New York, State of New York, have invented a new, original, and ornamental Design for an Educational Game Board, of which the following is a specification, reference being had to the accompanying drawing forming part thereof.

In the drawing:

Figure 1 is a plan view of an educational game board showing my new design.

Figure 2 is an edge view thereof.

I claim:

The ornamental design for an educational game board, as shown.

JULIAN J. FABERMAN.
